UNITED STATES PATENT OFFICE.

JOSEPH RAPSEVEZ, OF PHILADELPHIA, PENNSYLVANIA.

MUSICAL INSTRUMENT.

Application filed March 28, 1927. Serial No. 178,890.

My invention relates to musical instruments and more particularly to certain improvements in violins and has for its principal object to provide an instrument having means for amplifying the tones thereof.

This object, and other advantageous ends which will be described hereinafter, I attain in the following manner, reference being had to the accompanying drawings in which

10 Figure 1 represents a violin made in accordance with my invention,

Figure 2 a plan view of the horn element shown in Figure 1,

Figure 3 an enlarged sectional view taken substantially on line 3—3 on Figure 1, and

15 Figure 4 an enlarged cross sectional view taken on line 4—4 on Figure 1.

Referring now in detail to the drawings, the violin 5 is so well known in the art that 20 it needs no particular description other than that necessary for an explanation of my invention. Inserted in violin 5 is a horn 6 having an upturned bowl 7 and a flared mouth 8. Horn 6 is secured to blocks 9, 25 which are preferably glued to the back 10 of violin 5, by means of a strap 11 and is so located that bowl 7 overlaps a portion of F's 12 while its edge is disposed in close proximity to sound bar 13. Mouth 8 extends from violin 5 at an angle to neck 14 and is so 30 disposed, relatively thereto, that it does not interfere with the fingering of the strings 15. The upper end of horn 6 is held in such position, by passing through an aperture 35 formed in the side 16 of the violin body, that its body part does not come in contact with either the back 10 or the front 17 of the violin.

In playing the instrument, the vibrations 40 of strings 15 are transmitted by bridge 18 to front 17, causing vibration thereof which is amplified by sound bar 13, while some of the vibrations are transmitted to the back 10 by sound post 19.

45 In thus transmitting the vibrations, a great deal of their strength is lost or absorbed by the body of the violin and my invention is designed to amplify some of these vibrations. By disposing bowl 7 under a portion of F's 12 in close proximity to sound

bar 13, it is also close to sound post 19 and in a favorable position to receive a large number of vibrations set up by strings 15. These vibrations are greatly amplified by the horn so that the sound produced by the 55 horn greatly augments the sounds produced by violin 5, thus greatly increasing the volume of the combined instrument without increasing its size or changing its tone. By changing the size and tonal qualities of horn 6, the tonal effect produced by the violin is materially changed. The selection and installation of horn 6 is easily within the ability of any violin maker who possesses an ear for music and an instrument may be 60 produced which will meet the requirements of any individual.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the 75 appended claims.

I claim:—

1. A stringed musical instrument including a hollow violin body having front, back and side walls, a horn disposed partly within the body and extending through one of the side walls, and a bowl on the inner end of the horn having its opening disposed in close proximity to the front wall.

2. A stringed musical instrument including a violin body having F shaped apertures therein, a horn disposed partly within the body, and a bowl on the inner end of the horn covering a portion of said apertures.

3. A stringed musical instrument including a body having F shaped apertures therein, a sound board secured inside the body, a horn disposed partly within the body, and a bowl on the inner end of the horn disposed in close proximity to the sound board and overlapping a portion of the apertures.

4. In a violin having a hollow body, F-shaped apertures in its front wall, a sound bar within the body, and a sound post snugly fitted between the front and rear walls

of the body, means for amplifying sounds produced by the violin including blocks secured to the rear wall of the body, a horn secured to the blocks and extending through the side of the body, a bowl formed on the inner end of the horn in close proximity to the sound bar and sound post and overlapp-

ing a portion of the apertures, and a mouth formed on the horn exterior of the violin body.

In testimony whereof I have signed my name to this specification.

JOSEPH RAPSEVEZ.
